[57] CLAIM

The ornamental design for a combined pan and diaper pail and cover therefor, as shown and described.

DESCRIPTION

FIG. 1 is an exploded perspective view of a combined pan and diaper pail and cover therefor showing my new design;

FIG. 2 is a side elevational view thereof shown with the pan enclosed in the pail and the cover in place, the opposite side being a mirror image;

FIG. 3 is a rear elevational view thereof;

FIG. 4 is a front elevational view thereof;

FIG. 5 is a top plan view thereof; and,

FIG. 6 is a bottom plan view thereof.

FIG. 1

FIG. 2

FIG. 3

FIG. 5

FIG. 6

FIG. 4
